ELECTRON DISCHARGE DEVICE

Heinz Erwin Kallmann, Ealing, London, and Otto Klemperer, Iver, England, assignors to Electric & Musical Industries Limited, Middlesex, England, a British company

Application August 13, 1936, Serial No. 95,744
In Great Britain August 21, 1935

10 Claims. (Cl. 250—27)

The present invention relates to electron discharge devices.

It has been proposed to obtain electrical amplification by the so-called method of electron multiplication in which use is made of the fact that an electron impinging with suitable velocity on a solid body may cause several secondary electrons to be emitted. In a proposed arrangement for carrying this method into effect two electrodes, at least one of which is coated with photo-sensitive material, are placed opposite one another in an evacuated envelope. Also in the envelope and surrounding the space between these two electrodes is arranged a tubular anode. A generator of high frequency electrical oscillations is associated with the first mentioned two electrodes (which will hereinafter be referred to for convenience as the oscillator electrodes) by means of which high frequency alternating potentials are applied across them. The anode is connected through an output impedance such as a resistance to the positive terminal of a source of constant potential such as a battery, the negative terminal of which is connected to the electrical centre of the generator. The device operates in the following way.

The input signals are in the form of light of varying intensity, and this light is allowed to fall onto the photo-sensitive oscillator electrode. When this electrode is at a negative potential with respect to the oscillator electrode opposite, the photo-electrons liberated are accelerated towards the impinge upon this opposite electrode, and liberate secondary electrons therefrom, which, if the impact velocity of the photo-electrons is suitably chosen, are greater in number than the incident photo-electrons. The frequency of the alternating potentials applied to the electrodes is so chosen that the potentials of the electrodes are now reversed, so that the secondary electrons are accelerated towards the photo-sensitive electrode, and the process of production of secondary electrons will be repeated. Thus there will be produced an oscillating cloud of electrons rapidly increasing in density. The electrons may be prevented from spreading by the production of a suitable magnetic field. The anode surrounding the space between the electrodes has a positive potential, and has the effect of drawing off a certain fraction of the electrons from the space inside it. This current, passing through the output resistance gives rise to potential differences across the latter, which potential differences are used as the output potentials of the device.

Means are also associated with the device whereby the oscillation is prevented from building up indefinitely, so that variations in the light incident on the photo-sensitive electrode produce corresponding variations in the output potential. To this end the oscillation is periodically stopped, for instance by stopping the generator of oscillations, or by periodically applying to one of the oscillator electrodes a positive or negative pulse. Thus if the generator produces an oscillation having a frequency of 50 megacycles per second, the stopping pulse may recur at a frequency of 5 megacycles per second.

Now we have found that the range of potentials which may be applied to the anode to produce satisfactory amplification lie between very narrow limits (assuming the other factors to remain unchanged). When current flows in the anode circuit, the potential of the anode will be changed, and this change of potential is sufficiently great to upset the satisfactory working of the device, by causing changes in the current oscillating between the electrodes and in the background current, that is the current which is present in the device even when no light falls on the photo-sensitive electrode.

We have also found that if a curve is plotted showing the potential distribution along the axis of the device (distance along the axis being plotted as abscissa against potential as ordinate) the curve so obtained is saddle shaped, rising as the oscillator electrodes are approached and showing a minimum in the centre. The shape of this curve determines the time of flight of the electrons between the electrodes, and the slope of the ends of the curve determines the fraction of the electron cloud which is withdrawn by the anode. It will be seen therefore that variation in anode potential which will affect the potential distribution along the axis of the device may cause the time of flight of electrons from one oscillator electrode to the other to become different from the half period of oscillation of the potential on the oscillator electrodes, and may also adversely affect the equilibrium conditions.

The invention may best be understood by referring to the drawings, in which:

Figure 1 is a diagram showing the relation between anode voltage and anode current in an electron multiplier.

Figure 2 shows one form of the invention, and

Figure 3 shows a modified or alternate form of the invention.

The manner in which changes in anode potential affect the working of the device described

45

50

55

above may be seen from Fig. 1 of the accompanying drawings, which is a diagram representing the relation between anode voltage plotted along OX and anode current plotted along OY. The curve *a* shows the relation between anode current and voltage when no light is allowed to fall on the photo-electrically active oscillator electrode. It will be noted that the device exhibits a negative resistance. The dotted curve *b* shows the corresponding relationship when light of given intensity is allowed to fall on the photo-electrically active oscillator electrode. It will be noted that curve *b* has a negative slope of smaller value than curve *a*. These curves are obtained experimentally in the usual manner.

Referring to Fig. 1, let it be assumed that the device is given a voltage x on its anode, and no light falls on the photo-electrically active oscillator electrode. The anode current will then be given by y_1 . Now if light of a given intensity falls on the photo-electrically active oscillator electrode, in the absence of any anode load resistance, the anode current will rise to a value y_2 . The presence of an anode load resistance will however cause a drop in anode voltage due to the increase in anode current from y_1 to y_2 , and consequently the device will be working on a different portion of its characteristic. The amount of movement along the characteristic will clearly depend on the change in anode current, and hence on the intensity of light falling on the photo-electrically active oscillator electrode. Since the curves *a* and *b* have different slopes, the output current will not be proportional to the intensity of the incident light, and if the latter is a beam of varying intensity, a distortion of the variations will occur in the output of the device.

It is an object of the present invention to provide an improved electron discharge device of the kind hereinbefore referred to, in which the effect of variations in anode potential is diminished or removed.

According to the present invention, an electron multiplying arrangement comprising an evacuated envelope, two oscillator electrodes arranged within said envelope in spaced relation, means for applying alternating potential differences between said electrodes for the purpose of oscillating electrons between them, input means for varying the number of electrons oscillating between said oscillator electrodes, an anode surrounding or partly surrounding the space between said electrodes, and a circuit for maintaining said anode at a potential positive with respect to the mean potential of said oscillator electrodes, so that said anode is adapted to draw off some of said electrons, said circuit including an output impedance, there are provided means for diminishing or removing the effect of changes of potential of said anode on the electrostatic field between said oscillator electrodes. Such means may comprise a grid electrode surrounding or partly surrounding the space between the electrodes, and serving to screen this space from the anode, and means for maintaining said grid at a substantially constant potential positive with respect to the mean potential of said oscillator electrodes.

The invention in one embodiment will now be described with reference to Fig. 2 of the accompanying diagrammatic drawings.

Referring to Fig. 2 a discharge device comprises an evacuated cylindrical glass envelope 1 having disc shaped oscillator electrodes 2, 3 one electrode being mounted near each end of the en-

velope 1. Surrounding the space between the oscillator electrodes 2, 3 is a grid electrode 4 in the form of a cylinder; the grid may be made from a helix of wire round suitable supporting rods (not shown). Co-axial with the grid is arranged a tubular anode 5, which may be a separate metal cylinder as shown or may be in the form of a metallic deposit on the inside walls of the envelope 1. Between the two oscillator electrodes 2, 3, and externally of the envelope 1 is connected a parallel resonant circuit comprising a condenser 6 and an inductance 7, and means, such for example as a coil 8 coupled electromagnetically to the inductance 7, are provided for coupling a thermionic valve oscillator 9 to the resonant circuit 6, 7. The oscillations produced by the oscillator 9 may have a frequency of the order of 50 megacycles per second and be periodically stopped at a frequency of 5 megacycles per sec-

ond. The tubular anode 5 is connected through an output resistance 10 to the positive terminal of a source of potential 11, the negative terminal of which is connected to the electrical centre of the inductance 7. The grid electrode 4 is directly connected to a point on the source of potential 11 which is less positive than that to which the anode 5 is connected. One or both of the oscillator electrodes 2, 3 are coated with photo-electrically active material 13, and the electrodes may be treated in any known or suitable manner to increase the number of secondary electrons emitted.

A coil 12 carrying a direct current supplied from a suitable source not shown surrounds the envelope 1 and serves to produce a magnetic field in the neighborhood of the anode 5 and parallel to the axis of the latter.

In operation, light of varying intensity is allowed to fall on one or both of the oscillator electrodes 2, 3. In order to allow the light to fall on the oscillator electrodes one of these electrodes or the anode 5 may be provided with a suitable aperture, or may have a length which is shorter than the distance between the oscillator electrodes 2, 3. In the case where the anode 5 is in the form of a metallic deposit on the walls of the envelope 1, a part or the whole of the deposit may be made so thin as to be substantially transparent, to allow light to fall on the oscillator electrodes.

As already described, the electrons emitted from the illuminated electrode are oscillated to and fro between the electrodes 2, 3, and are increased in number at each impact on an electrode by the phenomenon of secondary emission, so that a cloud of electrons oscillating between the oscillator electrodes 2, 3 is rapidly produced.

The grid electrode 4, being held at a positive potential with respect to the oscillator electrodes 2, 3 draws off a certain fraction of the electron cloud. The electrons drawn off will pass through the interstices of the grid 4 and will be attracted towards and be collected by the anode 5, which is at a higher positive potential than the grid 4. This current in the anode circuit will set up potential differences across the output resistance 10.

Now since there is no resistance in the circuit 70 associated with the grid 4, it will remain at a constant potential, which may be adjusted to the value at which the device operates most favourably. The current flowing in the anode circuit will cause the potential of the anode 5 to drop 75

from the value when the oscillator electrodes are not illuminated, but since the anode 5 does not exert the withdrawing effect on the electron cloud, this change of potential will not affect the stability of the device.

If desired a second grid electrode 14 may be inserted between the grid 4 and the anode 5, and may be held at a potential less positive than either, for instance by connecting it to the negative terminal of the source of potential. The purpose of this second grid is to prevent secondary emission from the anode, caused by the impact of the electrons passing through the grids, from entering the space between the oscillator electrodes.

The invention is not limited to the case where the grid or grids and the anode are tubular as may be seen by referring to Figure 3 of the drawings. Furthermore, the invention is further not limited to the case where the primary electrons are photo-electrons liberated by light since the primary electrons may, for example, be derived from a heated cathode, the emission from this cathode being controlled in any known or suitable way, as by means of a control electrode the potential of which is changed in accordance with the input signal to be amplified.

By referring to Fig. 3 it may be seen that the anodes 20 and 21 are shown as flat plates positioned in parallel relation. The grid or grids have been omitted for clarity, but would, of course, be placed near each of the anode plates and at the inside surface thereof. The corresponding grids as well as the anodes may be connected together, either internally or externally. With this construction of the device, if the anode and grid or grids are considered as being on either side of the device, the light beam may be directed onto photo-sensitive cathodes, if such cathodes are used, from above or below and hence no provision need be made in the anode portions for allowing light to pass through them into the interior of the device.

As suggested above, the cathodes may be heated to produce an electron emission, and in Figure 3 is shown a pair of cathodes 22 with filaments 23 for heating the same. Current is supplied to the filaments 23 by the conductors 24 and to the cathodes by conductor 25. A control grid 26 is also provided in such case to control the flow of electrons from the cathodes. It is to be understood, also, that in some cases only one of the two cathodes may be electrically heated and in such cases the other cathode may be only a metal plate for supplying secondary electrons or it may be photo-sensitized in order that the primary electrons may be supplied as a result of light or heat, alternatively.

In such a form as shown in Figure 3, the potentials of the grids and anodes would prevent excessive loss of primary or secondary electrons from between the anodes in a direction parallel to the plane of the anodes and furthermore externally or internally produced electrostatic or electromagnetic fields may be provided for this purpose.

It is understood that various modifications may be made in the invention and it is desired that all such modifications be considered as falling fairly within the spirit and scope of the appended claims.

We claim:—

1. In an electron multiplying arrangement comprising an evacuated envelope, two oscillator electrodes arranged within said envelope in

spaced relation, means for applying alternating potential differences between said electrodes for the purpose of causing electrons to oscillate between them, input means for varying the number of electrons oscillating between said oscillator electrodes, an anode substantially surrounding the space between said electrodes, and a circuit for maintaining said anode at a potential positive with respect to the mean potential of the said oscillator electrodes, so that said anode is adapted to draw off some of said electrons, said circuit including an output impedance, and means for reducing the effect of changes of potential of said anode on the electrostatic field between said oscillator electrodes.

2. An arrangement as claimed in claim 1 wherein the last mentioned means comprise a grid electrode substantially surrounding the space between the electrodes, and serving to screen this space from the anode, and means for maintaining said grid at a substantially constant potential positive with respect to the mean potential of said oscillator electrodes.

3. An arrangement as claimed in claim 1 wherein at least one of said oscillator electrodes are coated with photo-electrically active material, and said input means comprise a source of light adapted to be varied in intensity.

4. An arrangement as claimed in claim 1 wherein the last mentioned means comprise a grid electrode substantially surrounding the space between the electrodes, and serving to screen this space from the anode, and means for maintaining said grid at a substantially constant potential positive with respect to the mean potential of said oscillator electrodes, and wherein at least one of said oscillator electrodes is coated with photo-electrically active material, and said input means comprise a source of light adapted to be varied in intensity.

5. An arrangement as claimed in claim 1 wherein said input means comprise a source of electrons and control electrode means for varying the number of electrons proceeding from said source into the space between said oscillator electrodes.

6. An arrangement as claimed in claim 1 wherein the last mentioned means comprise a grid electrode substantially surrounding the space between the electrodes, and serving to screen this space from the anode, and means for maintaining said grid at a substantially constant potential positive with respect to the mean potential of said oscillator electrodes, and wherein said input means comprise a source of electrons and control electrode means for varying the number of electrons proceeding from said source into the space between said oscillator electrodes.

7. An arrangement as claimed in claim 1, wherein the last mentioned means comprise a grid electrode substantially surrounding the space between the electrodes, and serving to screen this space from the anode, and means for maintaining said grid at a substantially constant potential positive with respect to the mean potential of said oscillator electrodes, and wherein said anode comprises two portions in electrical connection with one another and arranged one on each side of the space between said oscillator electrodes and said grid comprises two portions in electrical connection with one another and arranged between the two portions of said anode and the space between said oscillator electrodes.

8. An arrangement as claimed in claim 1 wherein the last mentioned means comprise a

grid electrode substantially surrounding the space between the electrodes, and serving to screen this space from the anode, and means for maintaining said grid at a substantially constant potential positive with respect to the mean potential of said oscillator electrodes, and wherein between said anode and said grid there is provided a second grid electrode, and means for maintaining said second grid at a potential which is lower than either of the potentials applied, in operation, to said anode and to said first-mentioned grid.

9. An arrangement as claimed in claim 1, wherein the last mentioned means comprise a grid electrode substantially surrounding the space between the electrodes, and serving to screen this space from the anode, and means for maintaining said grid at a substantially constant potential positive with respect to the mean potential of said oscillator electrodes, and wherein said anode comprises two portions in electrical connection with one another and arranged one on

each side of the space between said oscillator electrodes and said grid comprises two portions in electrical connection with one another and arranged between the two portions of said anode and the space between said oscillator electrodes, and wherein between said anode and said grid there is provided a second grid electrode, and means for maintaining said second grid at a potential which is lower than either of the potentials applied, in operation, to said anode and to 10 said first-mentioned grid.

10. An electron multiplying device comprising an evacuated envelope, a planar thermionic cathode, a planar photoelectric cathode spaced from and parallel to the thermionic cathode, a cylindrical anode surrounding said cathodes, a shielding electrode concentric with and positioned within the anode, and input means for controlling a number of electrons between the two cathodes.
